UNITED STATES PATENT OFFICE.

GEORGE A. GOODSON, OF MINNEAPOLIS, MINNESOTA.

MEANS FOR REGULATING RECEPTOR-CLOCKS.

1,073,675.

Specification of Letters Patent. Patented Sept. 23, 1913.

Application filed October 17, 1910. Serial No. 587,431.

To all whom it may concern:

Be it known that I, GEORGE A. GOODSON, a subject of the King of Great Britain, residing at Minneapolis, in the county of Hennepin and State of Minnesota, have invented certain new and useful Improvements in Means for Regulating Receptor-Clocks; and I do hereby declare the following to be a full, clear, and exact description of the invention, such as will enable others skilled in the art to which it appertains to make and use the same.

My present invention relates to apparatus for regulating clocks by Hertzian waves and is particularly directed to the improvement of the mechanisms for this purpose disclosed and broadly claimed in my prior application S. N. 452,573, filed September 11, 1908, and in my prior application S. N. 545,022, filed February 21, 1910.

The present invention consists of the novel devices and combination of devices hereinafter described and defined in the claims.

My present invention is directed chiefly to the provision of simple and efficient means for preventing detrimental or interfering actions, by stray Hertzian waves or electro-magnetic oscillations which are not intended for action thereon, and which, in practice, has been found will be produced in certain localities and at various times, particularly by long natural electrical discharges, but also by other causes.

One highly important feature of the present invention is found in the modification of the means shown in my prior application S. N. 545,022 for opening the relay circuit and grounding the antenna, it having been found in practice that where it has been necessary to have the receptor mechanism at a considerable distance from the receptor clock, it is undesirable to have the antenna circuit running to and from the clock. In practice it has been found that during electrical storms, long trains of electro-magnetic waves, which are too long in duration to be taken care of by the operation of the selector device of the said latter noted prior application, will set the hands of the receptor clock, if the said hands are within the setting zone, to-wit, within the period commencing at $2\frac{1}{2}$ minutes before and extending to $2\frac{1}{2}$ minutes after every third hour.

Another important improvement relates to a safety cut-out which is so arranged that,

in case of a storm, the setting apparatus will be cut out before it has had time to operate on the hands of the receptor clock, and thus permits the hands to be set but once every three hours.

The present invention is illustrated in the accompanying drawings wherein like characters indicate like parts throughout the several views.

Referring to the drawings, Figure 1 is a front elevation of the receptor clock, some parts being broken away and some parts being removed; Fig. 2 is a side elevation of the parts shown in Fig. 1; Fig. 3 is a horizontal section taken on the line $x^3 x^3$ of Fig. 1; Fig. 4 is a detail in front elevation, showing the lightning cut-out device; Fig. 5 is a plan view of the parts shown in Fig. 4; Fig. 6 is a front elevation of the clock circuit cut-out; Fig. 7 is a diagrammatic view of the complete receptor mechanism; and Fig. 8 is a diagrammatic view of the modified form of the complete receptor mechanism.

In the detail description hereinafter given, the following classification of parts and notations thereof is made. Clock circuit cut-out—*a* and its powers. Lightning cut-out—*b* and its powers. Hand setting device—*c* and its powers. Double acting switch—*d* and its powers. Receiving aerial, coherer, decoherer, relay and selector—*e* and its powers. Receptor clock proper—*f* and its powers.

The receptor clock proper and hand setting device shown in the drawings, and in connection with which the said improvements are used, are preferably the same as those described in my prior application S. N. 545,022.

Referring to Fig. 6, the minute hand *f*¹ and the pinion *f*² are rigidly connected to the main arbor *f*³. The gear *f*⁴ engages the pinion *f*² in the ratio of three to one, thus making one complete rotation in three hours, which, by referring to said prior application, will be found to be the interval between the transmitter discharges. The gear *f*⁴ is provided with a short laterally projecting pin *a*¹, adapted to engage a short arm *a*² of a contact lever *a*³, pivoted at *a*⁴. The free end of the lever *a*³ has a downward projection adapted to engage a drop of mercury included in a hard rubber receptacle *a*⁶, through the bottom of which is inserted a contact pin *a*⁷ touching the mercury for con-

tact. To the opposite side of the lever a^3 and secured to it, is a heavy arm a^5 so that, normally, the downwardly projecting end of a^3 is held out of contact with the mercury 5 and is brought to rest against the pin a^6 , that is, when the stud a^1 is not engaged with the arm a^2 .

Lightning cut-out.—This device is shown in detail in Figs. 4 and 5. Referring to these figures, b^1 is a cam rigidly connected 10 with the main arbor f^8 , which also carries the minute hand f^1 . This cam engages a lever b^2 comprising two oppositely projecting arms and intermediately pivoted at b^3 . One end is adapted to engage a mercury contact cup b^4 and the other adaptable to be 15 caught and held after being raised by the cam, by a lug or projection b^5 on the hand-setting armature lever c^1 . The armature lever also carries an inwardly projecting 20 stud b^6 adapted to engage and hold the lever b^2 in the raised position until the clock has been set and the armature lever is receding to its normal position when it will drop, 25 thus disengaging itself from the mercury cup and opening the circuit. The cam and the minute hand are set diametrically opposite on the main arbor.

Double acting switch.—This is shown in 30 Fig. 7, and consists of the ordinary type of polarized relay, except that a contact is made with either throw of the armature lever d^1 , the said contacts being shown by the letters d^2 and d^3 . The magnets are 35 double wound, one being a low resistance winding d^4 which is in series with the clock setting circuit, and a high resistance winding d^5 .

Receiving aerial, coherer, decoherer, relay and selector.—These devices are shown in 40 Fig. 7 and Fig. 8. The selector is a modification of that described in my former application 545,022, and consists of a slow acting armature lever e^1 adapted to make contact 45 with e^2 through the step up lever e^3 at the end of the transmitted signal from the master clock.

The receiving aerial, coherer, decoherer and relay are ordinary wireless instruments. 50 *Operation.*—Let us assume that the clock is five minutes of six, as in Fig. 6. At this time and for ten minutes more, the stud a^1 is holding the lever a^3 in contact with the mercury in the cup a^6 . If there has been no 55 atmospheric or other electro-magnetic disturbance to make the selector contact and thereby move the hand-setting armature lever, the lightning cut-out lever b^2 will, at one end, be engaged in the mercury cup b^4 and, at the other end, be locked by the lug b^5 . Thus a metallic contact is made from one cup to the other by way of the clock work. Two wires 1 and 2 run from the coherer receptor to the clock, the current entering the clock-setting magnet c^2 ,

thence running to the mercury cup a^6 by wire 3, through the two levers and clock frame and out by way of wire 2. Either lever, therefore, can break the circuit. Wire 2 is connected to one terminal of the low 70 resistance winding d^4 on the double acting switch, the other terminal running to the batteries 5, thence to the selector contact e^2 through 6. Wire 1 is connected with the other selector contact e^1 . 71

The high resistance winding d^5 of the double acting switch is connected across the two selector contacts e^2 and e^1 , through the wires 7 and 8. Thus a high resistance circuit is made, when the clock is in the aforesaid position, through the clock and double acting switch. The clock-setting magnets c^2 will not operate on the slight current that passes, but the relay armature d^1 is drawn into contact with d^3 , the purpose of which 80 will be explained later. On the release of either mercury contact in the clock, this armature lever will be drawn into contact with d^2 . 81

Returning now to the clock in the position 9 stated—suppose, at this instant, the selector, for any reason whatever, works and makes contact between e^1 and e^2 . The current on the completion of the circuit energizes the magnet c^2 and attracts the hand-setting armature lever c^1 , which immediately strikes the periphery of the setting cam c^3 (the V notch not coming into position until $2\frac{1}{2}$ minutes of the hour), releases the lever b^2 from the lug b^5 . The lever b^2 then drops upon the stud b^6 (but does not release from the cup b^4), until the circuit is broken at the selector contacts, when the armature c^1 recedes and the lever drops upon the small side of the cam b^1 , thus releasing itself from the 1 mercury cup b^4 . Thus it is seen that the clock cannot repeat this operation until another three hours have passed, or until both mercury cups are again in contact. If there had been no disturbance before the hour, the 1 clock would have received the signal from the master clock and righted itself, opening the circuit as before.

Returning to the double acting switch. As before described, the contact was made 1 on the side d^3 when both mercury cups a^6 and b^4 were in contact with the levers a^3 and b^2 . This closed the relay circuit from the coherer e^4 , through wire 9, armature lever d^1 , contact d^3 , wire 10, thence through 1 the relay magnets e^6 , through wire 11, through the battery 12 and thence returning to the other side of the coherer e^4 . Hence, it is evident that the relay circuit is only closed while the contacts in the clock are 1 closed, which is only for a short interval every third hour. An opening of the magnet circuit of the double acting switch reverses the contact to d^2 from d^3 , thereby opening the relay circuit and short-circuiting 1 the circuit.

ing the coherer e^4 , through wire 13, contact d^3 , armature d^1 and wire 9, thus making the coherer inoperative and protecting it from all electro-magnetic influences for three

6 hours.

When the selector contacts e^1 and e^2 close, thus operating the clock magnets, the high resistance winding d^5 , on the double acting switch, is short-circuited. This condition 10 would reverse the armature on said relay and render the coherer inoperative too soon. Hence, the low resistance winding on the said switch is in series with the clock-setting circuit, to retain the armature of the relay 15 in the proper position, that is, in the same position as the high resistance coils place it.

The modification shown in Fig. 8, of the complete receptor mechanism, differs from Fig. 7 chiefly in that three wires are used 20 in place of two between the coherer, receptor and the clock, and that the low resistance winding on the double acting switch is dispensed with. The circuit, including the said switch magnet winding, is made through 25 the two mercury cups a^6 and b^4 in the clock and includes a battery 12. The switch, therefore, performs the same functions as shown in Fig. 7. The clock-setting circuit is the same as that in Fig. 7, except that it does 30 not include the switch magnets.

The operations of the selector, tapper-back and relay were described in my former patent application S. N. 545,022.

What I claim is:

35 1. The combination with a clock, of clock setting mechanism sensitive to Hertzian waves, operative at predetermined intervals to set the clock during a predetermined period of said interval, and means also sen-

sitive to Hertzian waves operative to throw 40 the normal clock setting mechanism out of action and thus cause setting of the clock to be skipped during the next setting interval.

2. The combination with a clock, of clock setting mechanism sensitive to Hertzian 45 waves, operative at predetermined intervals to set the clock during a predetermined period of said interval, means also sensitive to Hertzian waves operative to throw the normal clock setting mechanism out of action 50 and thus cause setting of the clock to be skipped during the next setting interval, and clock actuated means for restoring the said clock setting mechanism to operative condition, thereby rendering the same operative 55 during a second following clock setting interval.

3. The combination with a clock, of clock setting mechanism sensitive to Hertzian 60 waves, normally operative at predetermined intervals to set the clock during a predetermined period of said interval, means also sensitive to Hertzian waves operative during 65 an interval which includes but is longer than the clock setting period, for throwing the said clock setting mechanism out of action during the next following clock setting interval, and clock actuated means for restoring said clock setting mechanism to operative condition for action during a second 70 following clock setting interval.

In testimony whereof I affix my signature in presence of two witnesses.

GEORGE A. GOODSON.
